UNITED STATES PATENT OFFICE.

WILLIAM F. KNAPP, OF DENVER, COLORADO.

HASP LOCK.

Application filed January 18, 1921. Serial No. 438,159.

To all whom it may concern:

Be it known that I, WILLIAM F. KNAPP, a citizen of the United States, residing at Denver, in the county of Denver and State 5 of Colorado, have invented new and useful Improvements in Hasp Locks, of which the following is a specification.

This invention relates to locks of the type wherein a staple is used in connection with 10 a hasp, the invention having for its object the provision of a staple supporting plate designed to accommodate means associating with the padlock or the like, whereby the padlock is permanently attached to the said 15 plate to thereby prevent loss of the lock when the latter is not in use.

The nature and advantages of the invention will be better understood when the following detail description is read in connection 20 with the accompanying drawing, the invention residing in the combination, construction and arrangement of parts as claimed.

In the drawing forming part of this application, like numerals of reference indicate the similar parts in the several views and wherein:—

Figure 1 is a view of the staple supporting plate constructed in accordance with 30 one embodiment of the invention.

Figure 2 is a similar view of a modified form.

Figure 3 is a similar view of another modified form of the invention.

Figure 4 is a similar view of a still further modified form.

Referring to the drawings in detail particularly Figure 1, 10 indicates a plate adapted to be secured to a suitable support 40 by means of fastening elements 11, the plate supporting staple 12 is used in conjunction with a hasp (not shown). The plate 10 has a depending portion 13 which is of a width substantially of the width of 45 the plate 10 being formed to provide a right-angularly disposed extension 14 having a loop 15 and an opening 16. A padlock 17 of any well known construction is attached to one end of a flexible element 50 such as a chain or the like indicated at 18, the opposite end of this element being secured to the opening 16 in the extension 14. When the hasp has been separated from the staple 12, and the lock is not in use, the said 55 lock can be suspended from the plate 10 to

prevent its loss, or the shackle of the lock may be arranged within the loop 15 to support the lock in a manner shown in Figure 1 so it can be readily and quickly obtained for use when desired.

In Figure 2 I have shown a modified form of the invention wherein the staple is indicated at 20 and mounted upon a plate 21 having a depending portion 22. Carried by the depending portion 22 is a pair 60 of loops 23 and 24 respectively, the staples being arranged at right-angles to the staple 20 and in short embodied relation. The lock 25 is secured to one end of a flexible element 26, the opposite end of the said arrangement being secured to the loop 24. When the lock is not in use the shackle thereof is positioned within the loop 23 so that the lock may be supported in the manner shown in Figure 2.

In Figure 3 I have illustrated another modified form of the invention wherein the staple is indicated at 27, the staple being mounted upon a plate 28 having an offset portion 29 provided with an aperture 30. This offset portion is arranged at one side of the plate 28 while adjacent the opposite side of the plate is an extension 31, which extension is bent upon itself to provide a loop 32, the terminal of which loop is secured as 70 at 33 to the plate 28. The lock 34 is secured to one end of a flexible element 35, the opposite end being secured to the aperture 30 of the plate 28. When the lock is not in use the shackle of the lock is supported 75 within the loop 32 as shown in Figure 3.

In Figure 4 I have illustrated a further modified form of the invention wherein the staple is indicated at 36 and arranged upon a plate 37 which is similar in construction to the plate 10 shown and described in connection with Figure 1. The lock 38 is secured to one end of a flexible element 39, the opposite end of the said element being secured 80 within the opening 40 provided in the right-angular extension 41, this extension being formed to provide a loop 42. The lock 43 is equipped with a hook 44 which is adapted to be positioned within the loop to support the lock upon the plate in the manner illustrated. The lock 43 in this particular instance is not provided with a shackle, and for which reason the hook 44 is used.

While it is believed that from the foregoing description, the nature and advan-

tages of the invention will be readily apparent, I desire to have it understood that I do not limit myself to what is herein shown and described, and that such changes may be resorted to when desired as fall within the scope of what is claimed.

What I claim is:

1. The combination with a lock, of a plate, a staple mounted on said plate, a flexible element terminally connected with

the plate and lock, and a loop carried by said plate for supporting said lock.

2. The combination with a lock, of a plate, an extension projecting from said plate, a flexible element terminally connected with the plate and said lock, and a loop carried by said extension for supporting said lock.

In testimony whereof I affix my signature.

WILLIAM F. KNAPP.
